(57) **CLAIM**

The ornamental design for a display screen or portion thereof with graphical user interface as shown and described.

DESCRIPTION

1. Display screen or portion thereof with graphical user interface

1.1: Front

1.2: Front

The appearance of the transitional graphical user interface sequentially transitions between the images shown in FIGS. 1.1-1.2; the process or period in which one image transitions to another image forms no part of the claimed design; for all figures, the broken lines showing a display screen or portion thereof with graphical user interface form no part of the claimed design; the grayscale tones displayed in the figures are intended to depict tonal contrast, and not any particular shade or tone of color.

1 Claim, 2 Drawing Sheets
